UNITED STATES PATENT OFFICE.

JAMES A. BURKE, OF CHICAGO, ILLINOIS, ASSIGNOR TO HIMSELF, CHARLES F. BLAKELY, CHARLES E. TUERK, AND ROBERT BUCKINGHAM, ALL OF SAME PLACE.

PRINTER'S GALLEY.

SPECIFICATION forming part of Letters Patent No. 242,748, dated June 14, 1881.

Application filed March 14, 1881. (No model.)

To all whom it may concern:

Be it known that I, JAMES A. BURKE, residing at Chicago, in the county of Cook and State of Illinois, and a citizen of the United States, have invented new and useful Improvements in Printers' Galleys, of which the following is a full description, reference being had to the accompanying drawings, in which—

Figure 1 is a top or plan view; Fig. 2, a longitudinal section on line $x-x$ of Fig. 1; Fig. 3, a detail, being a transverse section enlarged, on line $y-y$ of Fig. 1; Fig. 4, a detail, being a face view and vertical section of the pressure-plate or guard-plate which protects the face of the end of the galley; Fig. 5, a detail, being a top or plan view of the open end of the galley, showing the retaining or side stick, end clamp, and means for securing the clamp to the stick; Fig. 6, a side elevation of the retaining or side stick; Figs. 7 and 8, details showing a modification in the construction of the hook end of the side-stick.

The object of this invention is to secure the type matter in the galley in a secure and firm manner without any delay, inconvenience, or trouble, and have the means for doing the work always at hand and ready for use.

My invention consists, essentially, in the combination, with the printer's galley, of a retaining or side stick provided with a raised portion at one end to fit the galley end piece, and a catch or hook at the other end to engage the galley-bottom at its open end for locking the stick and galley together, all as hereinafter more fully described.

The invention embraces other features of construction and combination, which will be specifically described hereinafter, and pointed out in the claims.

In the drawings, A represents the retaining or side stick; B, a galley of the ordinary form; C, the adjustable foot-piece or end clamp; D, the type; E, the adjustable hook-plate; a , the raised end of the side-stick; b , the opening for the galley end piece; c , the set or thumb screw; d , the guard or pressure-plate; e , the hook; f , the strap connecting the piece C with the stick A; g , the tongue or flange on the strap f ; h , the groove to receive the tongue or flange g ;

i , the adjusting-slots in the end piece, E; j , the set-screws for holding the end piece, E.

The retaining or side stick, A, may be made of malleable iron or other metal or wood, or any other suitable material which can be cast or otherwise formed into shape, and in form is rectangular, square, or other shape, so that the face or side which comes in contact with the type will fit snugly and press evenly and uniformly against the type, and its bottom will rest on or be parallel with the bottom of the galley. One end of this stick has a raised portion, a , which extends up and over the end piece at the closed end of the galley, an opening, b , being left or formed therein to receive such end piece, which opening is of greater width than the width of the end piece. The outward downwardly-projecting portion of this raised portion a has a screw-threaded opening to receive the shank of a set or thumb screw, c , the end of which can be brought into contact with the face of the galley-piece, so as to lock the stick firmly in position; and, as shown, in order to prevent the end of the set-screw from injuring the galley end piece a guard-plate, d , is provided, having a slot therein to receive the portion a and suspend the plate, so that the downward portion thereof will come against the galley end piece and receive the end of the set or thumb screw c , the other portion of the plate d resting on top of the horizontal portion of a . The other end of this stick A is provided with a hook or lip, e , which projects down and fits over or against the edge of the bottom at the open end of the galley. As shown in Figs. 2 and 6, this lip or hook e is formed with the stick, but it may be formed of an independent piece, as shown in Figs. 7 and 8, in which it is on a plate, E, which plate is provided with slots i to receive set-screws j , by means of which it is attached to the bottom of the stick A. This form of construction enables the hook to be adjusted so that it can be made to hook over the end of the galley, which differ to a slight extent in length, the piece or plate E being capable of being moved in or out to the extent of the length of the slots i , to adjust the hook e accordingly.

Other forms of hooks or lips than those

shown may be used at this end of the stick A, to long as they are capable of connecting the stick with the galley-bottom at the end, and the other end of the stick need not have the 5 precise construction for the raised portion A shown, as such portion may be in the form of a regular goose-neck or curve, or of some other form that will allow it to drop over the end piece of the galley, so that the stick can lie 10 within the galley.

The galley B may be of any of the ordinary and well-known forms of construction for printers' galleys, having side pieces and an end piece attached to the bottom, which is usually 15 made of sheet-brass or some other thin material.

The foot-piece or end clamp, C, may be made of a single piece of malleable iron, or other suitable material, bent or otherwise formed 20 to have two portions standing at right angles to each other, one of the portions to engage the face of the type and the other to fit or be in contact with the face of the stick, as shown in Fig. 1. This piece C is adjustable 25 on the stick A, and is secured thereto by means of a strap, f. This strap f is attached to the foot-piece C and embraces and clamps the side-stick, as shown in Fig. 3, and it is provided with the turned-in lip or flange g, which enters 30 a groove, h, formed in the side of the stick, the other side of the strap being secured to the arm or limb of C rigidly, by brazing, soldering, or otherwise, or it may be secured by means of a set-screw, as shown in Fig. 5. 35 When secured in this manner, or by passing the strap entirely around the stick and the limb of the clamp, if desired, a sliding wedge may be used for the purpose of holding the clamp firmly against the type, or this could be 40 done by using a set-screw in place of the sliding wedge.

The form of stick shown, having the raised portion a with an opening, b, is primarily designed for use on old galleys, where it is not 45 convenient or possible to change the construction of the galley, and this construction will also be found well adapted for use on new galleys; but, if desired, such new galleys might have the end piece slotted longitudinally, and 50 the end of the stick be provided with a tongue or extension to pass through the slot and receive a set or thumb nut for securing it in a firm manner.

As shown, the pressure or guard plate d is 55 suspended from the neck a, but such guard-plate, or its equivalent, might be in the form of a metallic strip secured to the outer face of the galley end, against which the end of the set-screw would bear.

60 The face of the type is omitted, and the body thereof is alone indicated by D.

When not in use the side-stick is shoved over against the side of the galley, which can

be easily done by loosening the set screw or nut, and when in position can be held so as 65 not to interfere with or be in the way of placing the type on the galley by setting the screw or nut to place.

In use, when a proof is to be taken of the matter on the galley, the stick A is brought 70 in contact with the type and pressed firmly against the same, so as to hold it snugly between the face of the stick and the side piece of the galley, and the stick is then secured by tightening the set-nut or set-screw. The end 75 clamp is then shoved up so that its arm will come in contact with the end face of the type, and then secured, holding the type firmly in the space which it occupies on the galley, so that the operation of taking a galley-proof will 80 not disarrange the type or injure them in any way. When the proof is taken the end clamp can be shoved down and the side-stick loosened and shoved out of the way, leaving the matter 85 so that it can be readily formed into shape for printing.

This stick furnishes a ready means for securing the type, which is always at hand, in position for use, and which, in use, will do its work effectually and in a reliable manner.

What I claim as new, and desire to secure by Letters Patent, is—

1. The combination, with a printer's galley, of a retaining or side stick provided with a raised portion to fit over the galley end piece, 95 a catch or hook to engage the galley-bottom at the open end, and means, substantially such as described, for confining the stick in its adjusted position, essentially as and for the purpose set forth.

2. The combination, with a printer's galley, of a retaining or side stick provided with a raised portion to fit over the galley end piece, and means, substantially such as described, to engage the galley-bottom at the open end, and 105 a set-screw for confining the stick in its adjusted position on the galley, essentially as and for the purpose set forth.

3. A retaining or side stick, A, adapted to be secured at one end to the galley end piece, 110 in combination with the adjustable plate E, having the catch or lock for connecting the stick to galleys which vary slightly in length, substantially as specified.

4. The combination, with a printer's galley, 115 of a retaining or side stick having a raised portion, a, to set over the end piece of the galley, and provided with an adjustable foot-piece, and a hook or catch for engaging the bottom of the galley, and means, such as described, for confining the stick in its adjusted position on the galley, substantially as described.
